[57] CLAIM

The ornamental design for dental attachment tool, as shown and described.

DESCRIPTION

FIG. 1 is a perspective view of a dental attachment tool supporting a mirror according to our new design;

FIG. 2 is a side view thereof;

FIG. 3 is a top plan view thereof;

FIG. 4 is another perspective view of an alternate embodiment of the attachment tool supporting a shield;

FIG. 5 is another side view thereof; and,

FIG. 6 is another top plan view thereof.

The broken line showing is for illustrative purposes only and forms no part of the claimed design.
